UNITED STATES PATENT OFFICE

2,542,358

EXTENSIBLE CONNECTOR FOR BRACELETS
OR THE LIKESaul Ritter, New York, N. Y., assignor of one-half
to Marvin J. Bruner, New York, N. Y.

Application September 21, 1945, Serial No. 617,816

7 Claims. (Cl. 24—71)

1

This invention relates to bracelet connectors and pertains more particularly to extension attachments for wrist watch bracelets or the like.

Connectors of the type to which the present invention relates have been made in various forms, one of the more popular constructions including a plurality of foldable members to provide a take-up means to hold a flexible bracelet or strap firmly against the wrist to retain a watch in place. The foldable members are usually hinged together and when open or positioned end to end provide the desired extension and when folded one upon the other the required take-up or contraction is provided.

It has also been found desirable to provide an additional slidably extension so that when the hinged foldable members are folded or in a contracted position the slidably-member or extension may provide for an additional take-up or contraction to avoid any looseness or play in the strap. On the other hand if the operation of closing the connector brings the strap too tightly against the wrist it may be released by extending the slidably-member. The foldable member type of connector is generally formed with a top member having flanges over-lapping a bottom member and it has been a problem to provide the desired long wearing rugged structural means of holding the members in closed position.

Heretofore most foldable member structures were provided with oppositely engageable lugs and detents so arranged as to frictionally hold the members in fixed relation. This type of retaining means, however, was subject to wear and failed to properly hold the members to the extent required for the practical long life expected in a commercial product of this type.

In accordance with the present invention foldable members may be readily and easily folded in the usual manner in combination with what may be termed a latch-assembly which is automatically operated as the members are brought into folded relation.

Furthermore, the latch-assembly is so constructed that a slight pressure upon the foldable members causes the latch to operate and retain the members in fixed relation. Means are provided to tensionally control the retaining means to effect a positive locking action and to quickly and effectively hold the members in fixed relation.

In devices of this character it is essential that the operation of opening and closing the connector consist of simple and convenient operations. The present invention, therefore, provides a locking means so constructed that a light pressure on the foldable members when folded causes them to be positively locked in fixed relation and a slight force is sufficient to unlock the members.

The foldable members of a connector of the

2

type to which the present invention relates have their free ends connected to portions of a flexible bracelet which in turn are connected to a wrist watch. When closing the connector to hold a watch firmly on the wrist a bottom foldable member remains against the wrist and a top or cover member locks with the bottom member. Means are so arranged that an applied force or pull required to unlock the members is in the direction that the user would normally or naturally follow in attempting to lift the top member to separate or open the connector as will appear upon reference to the drawing and description of operation.

In my patent application Serial No. 617,817 filed September 21, 1945, now abandoned, I have shown and described a structure wherein a latch bar is provided cooperating with means on a foldable member whereby the members may be unlocked by manual movement of the latch bar. In the present invention the locking and unlocking function is attained by a relative movement of the two foldable members. A modification of the present invention is shown in my patent application Serial No. 24,791, filed May 3, 1948.

It is an object of the invention to provide a bracelet with an extensible connector having a plurality of members folded one upon the other which when folded are held in fixed relation by a tensionally controlled locking element.

Another object of the invention is to provide a bracelet with a connector having foldable members held in fixed relation by a latch member movable endwise to lock or release the foldable members.

Another object of the invention is to provide a connector comprising a plurality of foldable members which may be automatically locked when brought to folded relation and released upon a movement of one foldable member endwise, relative to another foldable member.

Other objects and advantages of the invention will be more fully understood by reference to the following description together with the accompanying drawings, in which:

Fig. 1 is a perspective view of the present connector with the members in folded relation;

Fig. 2 is a perspective view of the connector showing the foldable members in open position;

Fig. 3 is a perspective view of the underside of the top foldable member;

Fig. 4 is a view taken on line IV—IV in Fig. 1;

Fig. 5 is a view similar to Fig. 4 but showing the top and bottom members in adjusted relation to permit the members to unfold;

Fig. 6 is a view taken on line VI—VI in Fig. 4;

Fig. 7 is a view taken on line VII—VII of Fig. 4;

Fig. 8 is an enlarged plan view of the device taken on line VIII—VIII in Fig. 4;

Fig. 9 is a view similar to Fig. 8 but showing

the parts in different positions relative to Fig. 8;

Fig. 10 is an enlarged fragmentary view of a portion of the connector with parts broken away to show the cooperating latching means on upper and lower foldable members taken on line X—X in Fig. 6;

Fig. 11 is a fragmentary view showing the latching means ready to lock, and

Fig. 12 is a view similar to Fig. 11 but showing the latching means ready to release the foldable members.

A device constructed in accordance with the present invention may comprise a foldable member 10 which may be termed a bottom or receiver element, an intermediate member 11, and a cover-member 12 which latter may be termed a cover-member. Slidably disposed in the cover-member 12 is an extension or slide-member 13. The bottom-member 10 is hingedly connected at 14 to the member 11 which in turn is indirectly hingedly attached at 15 to the cover or top member 12. The member 11 although connected to the cover 12 is hinged to a spring pressed carrier or spring-bar 20 mounted on and movable relative to the cover 12, the operation and purpose of which will be hereinafter explained. An end 16 of the member 10 is connected to one end of a portion 17 of a flexible band, the other end of said portion may be connected to one side of a watch. End 18 of the slide-member 13 is connected to one end of a portion 19 of a flexible band, the other end of which may be connected to the other side of the watch in the usual manner as shown in dotted lines (Fig. 2).

In the present construction the member 13 is slidable in guide slots 21 formed from the side walls of the top member 12. One end of the slide-member 13 is provided with a pawl or spring tongue 22, which when the foldable members are folded, engages with teeth 23 formed in the intermediate member 11. Thus the slide member 13 in combination with the teeth provided on member 11 provides a pawl and ratchet mechanism to permit adjustment of the slide member 13 which may be held in an adjusted position.

It is obvious that the pawl and ratchet mechanism may be varied in construction to meet variations in any modified form of the present connector.

An important feature of the present invention is in the provision of a simplified latch and locking mechanism. This latch and lock includes the spring-bar 20 (see Figs. 6 to 9) movable in the cover or housing 12. The spring-bar 20 which serves as a latch bar is slidable against the top wall of the housing and is urged in one direction by a spring 25.

As will be noted this spring-bar 20 is disposed between the top wall of the cover 12 and the slide-member 13. One end of the spring-bar is provided with ears or partial side walls 26 which act as guides during movement along the guide slots 21 of the cover 12. An end 27 of the spring-bar extends into a housing 28 formed between the top wall of the cover 12 and an extension portion 29. Thus one end 27 of the spring-bar is tensionally engaged by the spring 25 which normally holds the spring-bar in its outer position with its end 31 engaging suitable stops to normally hold the hinge on the spring-bar flush with an end of the cover-member 12. The stops to engage the end 31 of the spring bar may consist of a peened or inturned end of the top wall of the cover member 12. The spring-bar 20 thus serves as a movable hinge support.

From the foregoing it will be evident that the spring-bar 20 carries the intermediate member 11 to which it is directly hinged and the bottom-member 10 which is hingedly connected to the member 11, thus the spring-bar 20, intermediate member 11 and bottom member 10 constitute a foldable assembly which as a unit is movable relative to, but carried by the cover 12.

By reason of the present construction, therefore, the cover 12 and the bottom-member 10 are movable relative to each other and serve as cooperating elements of a latch as will be explained. Thus when the foldable members are in folded relation the pawl 22 engages a tooth 23 on the member 11 and thereby holds the members 10 and 11 as a unit, the cover member 12 may be moved in opposition to the spring 25.

This relative movement between the cover 12 and bottom member 10 is, in accordance with the present invention, utilized to provide a latch mechanism. This mechanism comprises a plurality of inclined lugs or detents 32 formed in side walls 33 of the bottom-member 10. These lugs are so disposed as to engage with the edges of notches 34 formed in flanges 35 of the cover-member 12. It will be noted that several notches are provided on each flange of the cover-member to receive a similar number of lugs or detents on the bottom-member. By this arrangement of detents and notches the parts are more firmly held in locked relation and any relative play between the parts is avoided.

When the foldable members are pressed into folded or closed relation the inclined lugs 32 engage the edges of the notches 34 and as the members are pressed tightly together the bottom member 10 is moved in opposition to the spring 25 causing the lugs to slip past the edges of the notches whereupon the spring 25 causes a relative movement between the members 10 and 12 and the flanges 35 slip under the lugs 32 (see Fig. 10), thereby positively locking the foldable members in fixed folded relation. The slide-member 13 may then be adjusted to take up any slack bringing the pawl in contact with one of the teeth 23.

When it is desired to open the connector the cover member is grasped by the thumb and forefinger at the knurled portions 36 and force is exerted slightly upward and longitudinally of the members as in the direction of arrow X in Fig. 1 or 5.

The force thus applied causes the cover 12 to move endwise, since the other members are held as a unit by reason of their attachment to the bracelet on the wrist. This movement of the cover-member 12 brings the notches 34 in alignment with the lugs 32 and the edges of the notches 34 ride up the inclined lugs bringing about an automatic separation of the foldable members with the consequent opening of the connector.

In devices of the present character it is important to provide a simple and effective correlation of the movable parts as herein provided whereby the user may open or close the connector in a convenient and natural manner while at the same time providing a device as shown herein with a smooth surface free from projecting releasing means.

Although a preferred embodiment of the invention is shown and described herein it is to be understood that modifications and rearrangement of parts may be made therein without de-

parting from the spirit and scope of the appended claims.

What is claimed is:

1. An extensible connector comprising a cover-member, a spring-bar slidable in said cover-member, an intermediate member having one end hingedly connected to one end of said spring-bar, a bottom-member having one end hingedly connected to the other end of said intermediate member, means on said bottom-member cooperating with means on said cover-member for locking said members together under the action of said spring-bar, an extension member slidable in said cover-member, a pawl on said extension member, teeth on said intermediate member to engage said pawl when said members are in folded relation whereby said spring-bar is moved to release said members when force is applied to move said cover relative to said bottom-member.

2. A connector for a bracelet comprising a cover-member having a longitudinal flange provided with a notch, a spring bar movable endwise relative to said cover-member, a spring element for normally holding one end of said bar at one end of said cover, an extension-member slidable relative to said cover-member, a ratchet pawl on said extension member, an intermediate member having one end hingedly connected to said end of the spring-bar, ratchet teeth on said intermediate member to be engaged by said pawl when the connector is in contracted condition, a bottom member having one end hingedly connected to the other end of said intermediate member, a lug on said bottom member positioned to snap past said notch when the members are moved to contract the connector, said cover-member being movable with said spring-bar to cause relative movement between said cover and bottom members to dispose said lug under said flange to lock the members in fixed contracted relation.

3. An extensible connector for a bracelet comprising a plurality of foldable and unfoldable members to close or open said connector, consisting of a primary member, a spring bar slidable endwise in said primary member, a spring member for normally holding said latch-bar in a given position relative to said primary member, a second member hingedly connected at one end to said spring bar, a third member hingedly connected to said second member, means on said primary and third members cooperating to lock the members when in folded relation upon the endwise movement of said spring bar under the action of said spring member, said means operating to release said members upon an endwise movement of said primary member in opposition to said spring member and relative to said second and third members.

4. An extensible connector for a bracelet comprising a plurality of foldable and unfoldable members to close or open said connector, a primary member, a slide bar mounted in said primary member, a spring at one end of said slide bar for urging said bar in a given direction, a second foldable member having one end hingedly connected to the other end of said bar, a third member having one end hingedly connected to the other end of said second member, said primary member having notches, detents on said third member for engaging said notches to lock the members when in folded relation under the action of said spring, an endwise movement of said primary member relative to said second and

third members serving to disengage said detents and unlock said folded members.

5. An extensible connector for a bracelet comprising a plurality of foldable and unfoldable members for contracting and expanding said connectors including a cover member having a top and side walls, said side walls having notches, a slide bar mounted in said cover member between said side walls, a spring for urging said bar in one direction, an intermediate member having one end hingedly connected to said slide bar, a bottom member having one end hingedly connected to the other end of said intermediate member, flanges on said bottom member, detents on said flanges to engage said notches and lock said members when in folded relation, an endwise movement of said cover member relative to said bottom member serving to disengage said detents and notches to unlock said folded members.

6. An extensible connector for a bracelet comprising a plurality of foldable and unfoldable members for contracting and expanding said connector including a cover member having side walls provided with notches, a slide bar movable endwise between the walls of said cover, a spring at one end of said bar for normally retaining said bar in a given position, an intermediate member having one end hingedly connected to the other end of said bar, a bottom member having one end hingedly connected to the other end of said intermediate member, said bottom member having flanges provided with detents to engage said notches to lock the members when in folded relation, said detents being disengageable from said notches to unlock said members upon an endwise movement of said cover member relative to said bottom member.

7. An extensible connector for a bracelet comprising a plurality of foldable and unfoldable members for contracting and expanding said connectors including a cover member having a top and side walls, said side walls having notches, a slide bar mounted in said cover member between said side walls, a spring for urging said bar in one direction, an intermediate member having one end hingedly connected to said slide bar, a bottom member having one end hingedly connected to the other end of said intermediate member, flanges on said bottom member, detents on said flanges to engage said notches and lock said members when in folded relation, an endwise movement of said cover member relative to said bottom member serving to disengage said detents and notches to unlock said folded members, an extension member slidable in said cover member, a pawl on said extension member, teeth on said intermediate member for engaging said pawl to hold said extension member in adjusted position when the foldable members are disposed in foldable relation.
